UNITED STATES PATENT OFFICE.

FREDERICK E. SMITH, OF BROOKLYN, NEW YORK, ASSIGNOR TO THE YALE-AND TOWNE MANUFACTURING COMPANY, OF STAMFORD, CONNECTICUT.

INDICATOR FOR LOCKS.

No. 909,829.

Specification of Letters Patent.

Patented Jan. 12, 1909.

Application filed December 5, 1907. Serial No. 405,237.

To all whom it may concern:

Be it known that I, FREDERICK E. SMITH, of Brooklyn, in the county of Kings and State of New York, have invented certain new and useful Improvements in Indicators for Locks; and I do hereby declare the following to be a full, clear, and exact description of the invention, such as will enable others skilled in the art to which it appertains to make and use the same.

My invention relates to an improvement in indicators for locks, the object being to provide means for indicating at the outside, whether the door is locked from the inside.

With this object in view my invention consists in the parts and combination of parts as will be more fully explained and pointed out in the claims.

In the accompanying drawings, Figure 1 is a view in elevation partly in section of a section of a door showing my improvement applied thereto. Figs. 2 and 3 are views of the housing detached. Fig. 4 is a detached view of the plunger and Fig. 5 is a view similar to Fig. 1 of a modification.

The key holes of locks used on the doors of guests rooms at hotels, are usually out of line with each other, the key hole on the inside, being above the key hole on the outside, and my improvement is designed for use on a lock so constructed.

1 represents a door, 2 the lock, and 3 the inside key hole.

4 is the outside escutcheon plate, provided with the inwardly projecting housing 5, which latter rests within a recess formed in the outer face of the door. This housing, as shown in Figs. 1, 2 and 3, may be secured to the inner face of the escutcheon, by placing

the perforated ears 6 thereof over the stumps 7 integral with the escutcheon plates; and upsetting the stumps, and may be provided with an integral inner end 8, perforated for the passage of the plunger, or it may be

spun directly into the escutcheon plate, as shown in Fig. 5, and instead of having an integral end 8 as in Figs. 1 and 3, it may be provided with a separate end 8^a secured in place as shown in Fig. 5.

Mounted within the housing, is the plunger 9, provided at its inner end with a stem 10 projecting through the inner end 8 or 8^a of the housing, and through a hole in the lock in line with the inner key hole. This plunger normally rests with its outer end flush with

the outer face of the escutcheon, and is provided at its rear end with a flange 11 against which the spring 12 bears, the opposite end of the spring resting against the inner face of the escutcheon plate. This spring yieldingly holds the plunger in, flush with the outer face of the escutcheon plate, and when in such position, the stem 10 thereof is in the path of movement of a key entered into the key hole 3 from the inner side of the door, and when the key is inserted into the lock from the inside, it forces out the plunger and indicates to those on the outside, that the door is locked, or that the room is occupied. If the corridors or hallway be dark, the condition of the lock may be ascertained by running the hand over the escutcheon plate, the position of the plunger indicating whether the guest's key is in the lock, and thus avoiding the noise occasioned by the attempts to get in when the door is locked from the inside.

The stem of the plunger 9 is, preferably provided, as shown in Fig. 4, with a series of parallel annular weakening grooves 12^a, which are designed to materially assist the carpenter in cutting or adjusting the stem to conform to the thickness of the door.

It is evident that many slight changes might be resorted to in the relative arrangement of the parts shown and described without departing from the spirit and scope of my invention hence I would have it understood that I do not wish to confine myself to the exact construction herein shown and described, but

Having fully described my invention what I claim as new and desire to secure by Letters-Patent, is:—

1. In an indicator for locks, the combination with a lock, of a movable plunger normally in the path of the key and adapted to be pushed outwardly by the insertion of the key.

2. In an indicator for locks, the combination with a lock and an outer escutcheon plate, of a movable plunger mounted in the escutcheon plate and projecting into the path of the key of the lock, whereby when the key is inserted in the lock the plunger will be forced outwardly.

3. In an indicator for locks, the combination with a lock and an escutcheon plate, of a housing secured to the escutcheon plate in the plane of the key hole in the lock and a

plunger mounted in said housing and adapted to be forced outwardly by a key inserted in said key hole.

4. In an indicator for locks, the combination with a lock and an escutcheon plate, of a plunger carried by the escutcheon plate in the plane of the key hole in the lock, and adapted to be forced outwardly by a key inserted in said key hole, and a spring normally holding said plunger inwardly.

5. In an indicator for locks the combina-

tion with a lock, of a movable plunger mounted on the outside of the door and adapted to be pressed outwardly by the insertion of a key in the key hole of the lock. 15

In testimony whereof, I have signed this specification in the presence of two subscribing witnesses.

FREDERICK E. SMITH.
